CLAIM

The ornamental design for a head pillow as shown and described.

DESCRIPTION

FIG. 1 is a top front perspective view of a first embodiment of the head pillow;

FIG. 2 is a bottom front perspective view thereof;

FIG. 3 is a top plan view thereof;

FIG. 4 is a bottom plan view thereof;

FIG. 5 is a front elevational view thereof;

FIG. 6 is a rear elevational view thereof;

FIG. 7 is a side elevational view thereof;

FIG. 8 is an opposing side elevational view thereof;

FIG. 9 is a top front perspective view of a second embodiment of the head pillow;

FIG. 10 is a bottom front perspective view thereof;

FIG. 11 is a top plan view thereof;

FIG. 12 is a bottom plan view thereof;

FIG. 13 is a front elevational view thereof;

FIG. 14 is a rear elevational view thereof;

FIG. 15 is a side elevational view thereof; and,

FIG. 16 is an opposing side elevational view thereof.

The broken lines illustrate unclaimed portions of the head pillow of the second embodiment.

1 Claim, 8 Drawing Sheets
